UNITED STATES PATENT OFFICE

2,132,510

FLOAT WITH SIGNAL LAMP

William S. Goertzen, Newton, Kans.

Application March 17, 1937, Serial No. 131,423

3 Claims. (Cl. 43—17)

My invention relates to a float with signal lamp.

The object of my invention is to provide a float adaptable to night fishing and having an electric lamp battery and switch connected therewith, also a line upon which the float will slideably engage to set a fish hook carried by the line at a desired depth in stream or other body of water, and means to actuate the switch by a pull or jerk upon the hook whereby the lamp is illuminated.

A further object of my invention is to provide a float so that its body and parts connected may be die-cast.

15 A still further object of my invention is to provide a hollow float body having a seat for each end of a battery positioned in the float, one seat removable to exchange a dead battery for a live one and the other seat to carry an electric lamp.

20 A still further object of my invention is to provide a float having a shell and parts connected thereto made from metallic substance and die-cast the same.

These and other objects will hereinafter be 25 more fully explained, reference being had to the accompanying drawing forming a part of the specification, and in which like characters will apply to like parts in the different views.

Referring to the drawing:

30 Fig. 1 is a side view of the float, partly in section.

Fig. 2 is a top view of the float.

Fig. 3 is an enlarged sectional view of the lamp socket and battery seat, showing the switch and 35 portion of the float shell.

Fig. 4 is an enlarged side view of the line attaching means at the top of the float.

Fig. 5 is a sectional view of Fig. 4, on the diametrical axis thereof.

40 The invention herein disclosed consists of a float having a hollow body 1, preferably die-cast in the manufacture thereof, although the said body may be of sheet metal spun to a desired form, in case the latter material is used the shell 45 will be in two parts and joined on the center zone, but not shown in the present drawing.

Diametrically aligned and oppositely positioned in the shell of the body, which is spherical in form, are seat elements in which the ends of a 50 battery 2 is secured respectively, the upper seat consists of a tubular sleeve 3, partially extending into the shell and secured thereto fluidtight, the inner end functioning as a seat for the upper end of the battery, the outer end of the sleeve 55 has a lamp socket 4 secured therein fluidtight,

the outer end of which is concaved as at A, and being lined partially with a metallic reflector 5, the latter being apertured axial with the threaded bore of the said socket and adapted to engage snugly with the stem B of lamp 6, the said stem threadedly engaging and extending through the socket element to contact with the battery and adjacent thereto.

Extending upward and connected to the said reflector is a tongue 7, against the end of which will engage a spring tensioned arm 8 that is carried by a bridge 9, the ends of which are removably secured to the outer extending end of said sleeve 2, through one side of the bridge is a slot C, through which extends the arm 8 that is free to move reciprocatingly therein to and from contact with the end of said tongue 7, to make and break the electric circuit between the battery and lamp, the outer end of arm 8 has a clamp 10, arranged by bending the end portion thereof back on itself and in which line 11 will engage to move the arm downward responsive to a pull or jerk on a fish hook, carried by a downwardly extending portion of the line from the float, the hook not shown, and to permit such movement of the arm the line will be slack above the clamp as at E and retained in such position by tension of the coil spring F, integral with the said arm and the said spring being strong enough to carry the line and hook therebelow and the 20 float is carried by the line frictionally engaging in the aperture 12 of an elastic plug 13, secured within an annular ring 14, integrally joined to the top center portion of the said bridge.

One the lower side of the said float body is a 25 flange 15 integrally joined, externally threaded and through which the battery will pass when installing the same in the float, and being retained by a threaded cap 16 engaging on the flange fluidtight through the medium of a gasket 40 16', the said battery rests on a helical spring 17 carried by the cap, by which means the battery and lamp neck are secured in contact.

Positioned axially on the said cap 16 is an eye 18, positioned in a member 19, and through which 45 line 11 will slideably engage when the switch arm is being actuated.

To insure fluidtight engagement of the lamp in its socket, there is placed between said lamp and reflector a rubber washer 20, snugly engaging as the lamp is screwed in the socket.

It is now clearly shown that the bite or jerk 50 of a fish while fishing in the dark is readily observed and furthermore the said float will function in the light with or without its illuminating 55

capacity and such modification may be employed as lie within the scope of the appending claims.

Having fully described my invention, what I claim as new and desire to secure by Letters 5 Patent is:

1. In a float with a signal lamp, of the class described, comprising a hollow body, a sleeve inserted through the shell of the body, one end of the sleeve extending outward and having a re-10 movable bridge secured thereto, a flexible aper-tured plug and means to carry the same on the bridge, the body having a flange outwardly ex-tending and threaded externally, the flange being axially aligned with the sleeve, a threaded cap to 15 engage on the flange, a coil spring positioned in the cap, an element on the cap having an aper-ture therethrough, a lamp socket positioned in the sleeve and being spaced from the inner end thereof, a battery positioned in the body, one end 20 of the battery being carried by the inner end of the sleeve, the other end positioned within the flange and resting upon the spring, an electric lamp having a stem extending through the socket and in contact with the battery carried by the 25 sleeve, a spring tensioned arm secured to the bridge, and means connected to the lamp stem upon which the arm will engage when moved thereto, thereby closing the electric circuit.
2. In a float with a signal lamp, of the class 30 described, comprising a hollow body having a flanged opening communicating with the interior of the body, the flange being externally threaded, a threaded cap to engage on the flange as fluid-tight sealing means therefor, the said cap having 35 an apertured extension and a line to loosely engage in the aperture, a sleeve positioned in the shell of the hollow body and axially aligned with the flanged opening, a socket element secured in the sleeve and spaced from the inner end thereof,

the outer end of said socket having a concavity and being axially bored, the bore being threaded, a concavo-convex element centrally bored and seated in the concavity, a tongue secured to said concavo-convex element and positioned in paral-5 lelism with the axis of said socket member and extending outward therefrom, a slotted bridge secured to the outer end of the sleeve and extending across the end thereof, and a spring tensioned 10 arm secured to the bridge and adapted to extend through the slot and having a clamp on the outer end of the arm to engage the line rigidly, an elastic 15 plug and means to carry the same on the outer side of the bridge, by which means the line is slack between said plug and clamp, a battery 20 having one end positioned in the inner end of the sleeve, the other end positioned in the flanged opening, a helical spring seated in said cap as 25 tensioning means for the battery toward the sleeve, an electric lamp having a threaded stem 30 to engage through the bore of the socket in contact with the battery, all as and for the purpose 35 specified.

3. In a float with signal lamp, a hollow body, a sleeve partially extending into the body and a bridge positioned on the outer end of the sleeve, a lamp socket positioned in the sleeve and a re-flector carried by the socket, a battery positioned 35 in said body, one end of the battery being sup-ported by the inner end of the sleeve, means on 40 the body to carry the other end, an electric lamp secured in the socket and in contact with the bat-tery, switch means, one side of which is carried by the deflector and the other side of which is carried by bridge to make and break the electric 45 current between the battery and lamp, and a line carried by the float as actuating means for the 50 said switch means.

WILLIAM S. GOERTZEN.
